OFF-PEAK WATER HEATING SYSTEM

Clark M. Osterheld, Stoughton, Wis., assignor to
McGraw Electric Company, Elgin, Ill., a cor-
poration of Delaware

Application May 20, 1940, Serial No. 336,086

20 Claims. (Cl. 219—39)

My invention relates to fluid heating systems and more particularly to off-peak water heating systems.

An object of my invention is to provide a relatively simple and efficient off-peak water heating system adapted particularly to domestic water heaters.

Another object of my invention is to provide relatively simple and inexpensive means for delaying the energization of the heater of a water tank for a predetermined fixed length of time after the start of the off-peak period in case part of the water in the tank is hot.

Another object of my invention is to provide a water heating system that will effect heating of the water in the tank during the off-peak period only and at substantially the mid-portion of said period.

Still another object of my invention is to provide an off-peak water heating system that will start heating of the water either at the beginning of the off-peak period or after a certain fixed time delay depending on the amount of hot water remaining in the tank at the beginning of the off-peak period and that will stop heating of the water by thermostatic means before the end of the off-peak period.

Other objects of my invention will either be apparent from a description of several forms of systems embodying my invention or will be pointed out in the course of the description of these systems and particularly pointed out in the appended claims.

In the drawings,

Figure 1 is a horizontal sectional view through a domestic hot water tank to which my system has been applied, taken on the line 1—1 of Fig. 2,

Fig. 2 is a view in vertical section through a domestic hot water tank, the system embodying my invention being shown schematically therewith,

Fig. 3 is a modified system also embodying my invention,

Fig. 4 is a still further modification of a system embodying my invention,

Fig. 5 is a diagrammatic representation of the ordinary current load on a central station during on-peak and during off-peak hours,

Fig. 6 is a front view of a timer dial which is driven by a synchronous electric motor, and,

Fig. 7 is a modified form of part of the structure shown in Fig. 3 of the drawings.

Many central stations have made it a remunerative practice to provide off-peak water heating systems whereby fluid, and particularly water

for household use, may be heated at relatively low rates during the twenty-four hour period of a day when the total load on the station is relatively light, this time of course being that during the later part of the night. Thus it may be stated generally that the off-peak period may extend from 10 p. m. to 6 p. m. but in making such a statement I do not desire to be limited thereto or thereby, since the connected load on the circuits and its character will of course determine when the entire load on the central station is a minimum. Under these conditions of low load on its circuits the central station can afford to sell current at much lower rates than those prevailing during the so-called on-peak period of the day.

Referring now to Figs. 1 and 2 of the drawings, I have illustrated a domestic hot water tank 21 which is usually of circular shape and of much greater vertical axial length than its diameter. A tank of this kind may be provided with a cold water inlet pipe 23 and a hot water outlet pipe 25 and while I have shown these as extending axially or longitudinally of the tank, I do not desire to be limited thereto since other details as to the cold water inlet and valves, etc. may be provided, all in a manner now well known in the art. I have found it desirable to provide means whereby the inflowing cold water entering through the pipe 23 will have its force reduced as by a baffle 27, shown in Fig. 2 of the drawings, so as to prevent mixture of the cold water entering at the bottom of the tank, with the hot water still remaining in the upper part of the tank.

I may provide an outside thin sheet metal casing 29 around the tank 21 and fill the space therebetween with any suitable or desired kind of heat insulating material 31, now well known in the art. I may provide a plurality of supports 33 on which the tank and its casing may be mounted and the lower end of the tank may be spaced from the lower wall of the casing by a plurality of heat insulating blocks 35, all in a manner well known in the art.

I prefer to provide an electric heater 37 which may be of any suitable or desired kind but preferably is of the kind disclosed and claimed in my copending application Serial No. 284,881 filed July 17, 1939. An electric heating element of this kind is removably positioned within a tunnel member 39, all as set forth in my above mentioned copending application.

Referring now to Fig. 2 of the drawings, I have there illustrated a timing means which, for

convenience, has been illustrated as comprising a time-indicating disc 41 which, as shown in another view in Fig. 6 of the drawings, is driven by a small synchronous electric motor 43 which is connected to supply circuit leads 45 and 47 which are energized from a suitable source of supply of electric energy and while I have not shown any watt hour meter, such an instrument may be utilized, if so desired on the part of the central station to whose circuits the system embodying my invention may be connected. The motor 43 may drive the disc 41 as through a worm 49 or in any other way, it being understood that the disc 41 is rotated through one full revolution in twenty-four hours, or once each day.

The disc 41 is mounted on a shaft 51 which has mounted at its other end a second disc 53 which disc has different radial dimensions over its periphery. Thus the portion 55 has a relatively large radius and its peripheral length is such that it covers substantially one-third of the total periphery or in other words, its peripheral extent is equal to substantially that of the off-peak period, for purposes of illustration this being assumed to be an eight-hour period. A second portion 57 of relatively smaller outer radius, has a peripheral extent equal to substantially four hours, a third portion 59 is of still shorter radius and has a peripheral extent of two hours, and a fourth portion 61 has the same outer radius as portion 57 and is of ten hours in peripheral extent. I wish to point out here that my invention is not to be considered as being limited to the use of a separate disc, as it is obvious that the timer dial 41 may have a periphery of different outside radii as above described for disc 53.

A main heater-control switch includes a substantially rigid contact arm 63 and a resilient contact arm 65 normally out of engagement with each other, which latter is adapted to be operatively engaged by the peripheral surface of disc 53, the portion 55 thereof causing it to be moved, against its normal bias, into contacting engagement with contact arm 63 to thereby close said switch and to prepare the heater circuit so that it may be closed for energization of the heater by other means now to be described.

A thermostatically controlled switch designated generally by the numeral 67 comprises a tube 69 which is closed at its inner end and which has its outer end connected with the tank extending therethrough through a suitable opening, provision being made to make the connection leak-proof, all in a manner well known in the art. I may utilize any type of thermally-actuable means responsive to the temperature of the water surrounding the tube 69 but for simplicity I have shown an expansion rod 71 which is adapted to engage and actuate a spring contact arm 73 normally biased away from a substantially rigid contact arm 75. Thus when expansion rod 73 is cold, contact arms 73 and 75 will be disengaged from each other and when hot water surrounds the tube 69 the contact arms 73 and 75 will be caused to engage each other and close a circuit now to be described.

A substantially fixed rigid contact arm 77 cooperates with a resilient contact arm 79 which is normally biased into engagement with contact arm 77 but has its position controlled relatively thereto by a lug 81 secured to the outer end of arm 79 by the cam surfaces of rotating disc 53 which, as is evident from what has been said hereinbefore, will be turned through one full revolution in twenty-four hours. While no

means has been shown for adjusting the position of the disc 53 relatively to the disc 41, I desire it to be understood that the mounting of disc 53 on shaft 51 is such as to permit of doing so, so that the service man of the central station can so mount the disc 53 on shaft 51 as to have portions thereof aligned to agree with the off-peak time period considered proper by said central station. I desire also to point out that the peripheral extents of several cam surfaces 55, 57, 59 and 61 may be varied in accordance with the desires of the central station, such arrangement and adjustment being, of course, obvious.

The substantially rigid contact arm 75 is connected by a conductor 83 with the resilient contact arm 79 while the contact arm 77 is connected by a conductor 85 with the resilient contact arm 65. Contact arm 73 is connected by a conductor 87 with one end of the coil 89 of a contactor, the other end of the coil being connected by a conductor 91 to the supply circuit lead 41. Coil 89 is provided with the usual armature core adapted to energize and cause movement of a contact arm 93 which cooperates with a fixed contact 95 to control the circuit of the electric heater 37. It will be noted that contact arm 93 engages fixed contact 95 when coil 89 is de-energized.

Contact arm 93 is connected through a conductor 97 with contact arm 65. Contact member 95 is connected through a conductor 99 with the movable contact arm 101 of a thermostatically controlled main switch including in addition to the biased resilient contact arm 101 a substantially fixed contact arm 103. A tubular metal member 105 similar to tubular member 69 extends through the wall of tank 21 to which it is secured in a leak-proof manner and houses an expansion rod 107 which is adapted to engage and move contact arm 101 in such manner that arms 101 and 103 engage each other when the water surrounding tube 105 is cold. It may here be pointed out that I prefer to locate the thermostatically controlled switch comprising contacts 101 and 103, as well as the thermal actuating means therefor, in the lowermost part of the tank so that they will respond to the temperature of the water in the lowermost part of the tank and cause opening of the circuit through the electric heater 37 when substantially all of the water in the tank 21 has been heated to a predetermined temperature. While I have shown the tube 69 as located substantially in the mid-portion of the vertical dimension or length of the tank 21, I do not desire to be limited thereto since I may mount it higher up in the tank than shown in Fig. 2 of the drawings or farther down in the tank than as shown in Fig. 2 of the drawings, all as may be found desirable or called for according to the particular problem of the central station desiring to use my invention as regards their already connected load or as regards the off-peak heating system which they may desire to use.

Contact arm 103 is connected to one terminal of heater 37 while the other terminal of heater 37 is connected through a conductor 108 to lead 41.

The position of disc 53 as shown in the drawings is that occupied by it at the beginning of the off-peak period, which, for purposes of illustration, has been assumed to have a duration of eight hours and to begin say at 10 p. m. and to extend therefore to 6 a. m. the next morning. It will be noted that the engagement of contact arm 65

with the leading end of portion 55 of disc 53 has closed the switch comprising arms 63 and 65 it being understood that the disc 53 rotates in a clockwise direction, as shown by the arrow on the disc. The main switch has therefore been closed and has prepared the circuit through the electric heating means 37. If, now, the upper part of the tank is filled with hot water of a temperature to cause closure of the switch comprising contact arms 73 and 75, it will be evident that since contact arms 77 and 79 are also in engagement at this time, that coil 89 is traversed by a current, the circuit therethrough being substantially as follows: lead 45, contact arms 63 and 65, conductor 85, contact arms 71 and 79, conductor 83, contact arms 75 and 73, conductor 87, coil 89 and conductor 91 to supply circuit 47. This will energize the coil and cause it to move contact arm 93 upwardly to substantially the position in Fig. 2 of the drawings whereby the main energizing circuit of heater 37 is interrupted by the contact arms 93 and 95. As above noted, this is in case the upper part of the tank and particularly that predetermined part thereof filled with water immersing the tube 69, has a temperature high enough to cause closure of the switch controlled thereby.

Peripheral portion 59 of cam 53 is shown as having a peripheral extent equal to two hours of time and if no water is withdrawn from tank 21 during this two-hour period, the main heater 37 will remain deenergized during this length of time. At twelve o'clock a. m. the lug 81 will start to ride on the surface 61 of the disc 53 whereby contact arm 79 is disengaged from contact arm 77 and the energizing circuit through relay 89 is interrupted with the result that the energizing circuit through the heater 37 which was prepared, as above stated, by closure of the first main switch comprising contact arms 63 and 65, will then be fully closed, the heater energized and heating of the water in that part of the tank below tube 69 will start.

I wish to here state that while I have shown the peripheral extent of portion 59 as being equal to two hours, I do not desire to be limited thereto and the disc 53 may have the portion 59 of such peripheral extent as to call for a three-hour duration of such maintenance of the energizing circuit through heater 37 in open condition, if so desired.

I wish to further point out that the lowermost thermostatically controlled switch is desired to be effective to cause interruption of the energizing circuit through heater 37 before the end of the eight-hour off-peak period when the resilient contact arm 65 would operatively engage portion 57 of disc 53 whereby opening of the switch comprising contact arms 63 and 65 will be effected.

Referring now to Fig. 5 of the drawings, I have there shown a load curve 109 with certain assumed current values, the starting time of this curve being five o'clock a. m. It will be noted that the load value increases to some relatively high value and for illustrating purposes it has been assumed that this maximum load will be reached at substantially seven a. m. and will continue until around eight or nine o'clock at night, when the load value will start to decrease. While I have illustrated a substantially uniform load curve I am aware that such is not actually the case and that there will be more or less variation from such a uniform load value during the day, this of course, depending upon the partic-

ular conditions of demands for current by the loads connected to the circuits.

As noted, a relatively decided drop in load starts at about 10 p. m. and becomes pronounced at say the period from 1 a. m. to 5 a. m. when the load again starts to increase to its maximum at or about 7 a. m. If now we superpose an off-peak water heating load, indicated by the curve 111 in broken lines, as extending from 10 p. m. to 6 p. m., the part of curve 109 extending between the hours of 10 p. m. to 6 a. m. will be raised as shown by the broken line 113, so that the lines of the central station will have connected therewith a relatively appreciable load during the usual off-peak period.

Referring once again to the method of operation of the system shown in Fig. 2, it will be noted that if the upper part of the tank, say the upper half of the tank 21, is filled with hot water, the energization of the heater 37 will be delayed for a predetermined fixed time which may be made two hours, three hours, or some such value, so that the load caused by off-peak water heating demands will not be added immediately to the relatively high load value existing during the first part of the off-peak time. This delay feature of my invention causes a gradual rise of the hot water heater load on the power lines as indicated by the heater load curve 111, between the hours of 10 p. m. and 12 a. m., as shown in Fig. 5. If this delay feature were not present, the full water heater load would be superimposed on the power line load from other demands and would cause an undesirably big peak load on the power line between the hours of 10 p. m. to about 12 a. m. as indicated by the curve 114 in Fig. 5.

I wish to point out also that in case the upper part of the tank 21 is filled with hot water whereby a predetermined fixed time delay of energization of the heater 37 is effected, and if during this fixed time a demand for hot water arises and some hot water is drawn out of the tank so that the tube 69 and the thermal element are subjected to the temperature of relatively cold water, contact arm 73 will be caused to move out of engagement with contact arm 75 whereby the circuit through coil 89 is opened and the coil 89 is deenergized with the result that the second switch comprising contact arm 93 and contact member 95 will be closed and heater 37 will be energized. It is, of course, obvious that different domestic hot water-containing tanks, the heaters of which are connected to the circuits of a central station, may be partly filled with hot water sufficient to immerse tube 69 therein or they may have only a relatively small quantity of hot water in the upper part of the tank but out of engagement with tubular member 69. It is therefore evident that while some of the hot water tank heaters may be energized at the beginning of the off-peak period, this will not apply to all of them, and the supply of energy thereto begins at the beginning of the off-peak period or not depending upon the amount of hot water in the tank. I wish to point out that the auxiliary control thermostat comprising thermal element 71 and the contact members 73 and 75 controlled thereby is subject to the temperature of a predetermined portion of the water in the tank or to the temperature of the water in a predetermined part of the tank and does not in any way respond to the temperature of the water as existing throughout the whole length of the tank nor does it integrate the tem-

perature conditions existing in the water over the entire length of the tank.

Referring now to Fig. 3 of the drawings, I have there illustrated a dial 41 driven by a synchronous electric motor 43 through a worm 49, the dial 41 being mounted on a shaft 51 which carries also a disc 115. This disc has two portions, one portion 117 extending over about one-third of the periphery, i. e., its peripheral extent equals eight hours, the outer radius of the second portion 119 being less than that of portion 117. Substantially fixed contact arm 121 cooperates with a contact arm 123 the position of which is controlled by the disc 115 which is rotated in a clockwise direction. Contact arm 123 is normally biased out of engagement with contact arm 121 but has been moved into engagement therewith by reason of operative engagement of arm 123 with the portion 117 of the periphery of disc 115.

Tubular member 69, which is similar to that shown in Fig. 2 of the drawings and which may include a thermally actuatable expansion rod 71, controls a resilient contact arm 125 which is adapted to engage with a substantially fixed contact arm 127 when tube 69 is immersed in cold water whereby expansion rod 71 has been shortened sufficiently to permit contact arm 125 to engage contact arm 127.

A conductor 129 connects supply circuit lead 45 to one end of a relay coil 89, the other end of which is connected through a conductor 131 to contact arm 127. Supply circuit lead 47 is connected through a conductor 133 to one terminal of the electric heater 37 and has one end of a conductor 135 connected thereto, the other end of this conductor being connected with contact arm 123. Contact arm 121 is connected with contact arm 125 by a conductor 137. A contact arm 139 is electromagnetically controlled by coil 89 and is adapted to be caused to engage a contact 141 when coil 89 is energized.

Let it be assumed that the upper part, say the upper half of the tank 21, is filled with hot water so that thermal element 71 will be heated 45 and will have caused contact arm 125 to move out of engagement with contact arm 127 so that the energizing circuit through coil 89, which circuit extends through contacts 121 and 123, will have been opened so that contact bar 139 will be 50 in the position shown in Fig. 3 of the drawings. It will be noted that in this diagram only one electromagnetically controlled main heater switch is provided and if the upper part and particularly the upper half of the tank is filled with hot water, the energizing circuit through heater 37 is not closed at the time that contact arm 123 is moved into engagement with contact arm 121 at the beginning of the off-peak period when disc 115 is in the position shown in Fig. 3 of the drawings.

It is further obvious that if the upper part, say the upper half of the tank, is filled with cold water, contact arm 125 will be in engagement with contact arm 127 and the energizing circuit through relay coil 89 will have been closed at the start of the off-peak period so that contact arm 139 will engage contact 141 to thereby energize heater 37.

I provide also means for causing closing of the 70 energizing circuit through heater 37 by means of switch arm 139 and contact 141, this means including a contact arm 143 and a cooperating contact arm 145 which latter is normally biased out of engagement with arm 143 but is caused 75

to engage the same when arm 145 operatively engages the portion 117 of disc 115 a certain fixed time after the start of the off-peak period. Contact arms 143 and 145 are connected by conductors 147 and 149 with contact arms 125 and 127 respectively so that if contact arm 125 is maintained out of engagement with contact arm 127 for a fixed period of time because the upper part of the tank is filled with hot water, the energizing circuit through coil 89 will be closed after a predetermined fixed delay time when contact arm 145 is moved into engagement with contact arm 143 as hereinbefore stated. While I have shown the fixed time of delay of closure of the energizing circuit through heater 37 as being on the order of four hours, I am not limited thereto since, as shown in Fig. 7 of the drawings, I may mount contact arms 143 and 145 on a peripherally adjustable supporting arm 151 so that the operator or service man may easily and quickly adjust the angular position of the two contacts to suitably vary the fixed time of delay, it being understood that the main object of this delay time is to cause the period of energization of heater 37 to fall within the period of off-peak operation when the normally connected load is a minimum which, generally speaking, will be such that the mid-portion of the energization period of the water heater will coincide substantially with the mid-portion of the off-peak period itself.

Referring now to Fig. 4 of the drawings, I have there shown a still further modification of system embodying my invention and those parts which are the same as those shown in Figs. 2 and 3 of the drawings are provided with the same numbers. The shaft 51, which is driven by a synchronous electric motor 43, has mounted thereon a disc 153 which disc is provided with a portion 155 of larger radius which is relatively short peripherally. Following this portion there is a short peripheral portion 157, of lesser radius, which may be of such extent as to cover about two hours, then a portion 159 of greater radius, which may be of substantially six hours duration as to time and then a portion 161 which extends over about sixteen hours total. A relatively fixed contact arm 163 has a spring contact arm 165 cooperating therewith, the latter arm being normally biased out of engagement with arm 163 except when it is operatively engaged by the portions 155 and 159 of the disc 153 which is caused to turn in a clockwise direction the same as hereinbefore described for the contact actuating discs in the other figures of the drawings.

Supply circuit lead 45 is connected to contact arm 165 through a conductor 167 and contact arm 163 is connected through a conductor 169 to one terminal of a relay coil 171, the other terminal of which is connected through a conductor 173 and another conductor 175 with the other supply circuit lead 47. When the disc 153 is in the position shown in Fig. 4 of the drawings, which position it is intended to occupy at the beginning of the off-peak period, the energizing circuit through relay coil 171 will be closed and a contact arm 177 will be moved upwardly into the position shown in the broken lines where it will engage a contact member 179 which is connected to conductor 169 through a short conductor 181.

An auxiliary thermally controlled switch comprising the thermal element 71 in tube 69 is also provided and controls a spring contact arm 73 75 forcing it into engagement with contact arm 75

when element 71 is expanded because it is subject to the temperature of hot water positioned in the upper half of the tank.

Contact arm 171 is connected through a conductor 183 with contact arm 75 and with contact arm 101 of the thermal circuit controller subjected to the temperature of the water in the lowermost part of the tank, said thermal controller including particularly the expansion bar 107. Contact arm 103 is connected through a conductor 185 with one terminal of heater 37, the other terminal of which is connected through a conductor 187 with conductor 175 and therefore to the other supply circuit lead 41. Contact arm 73 is connected through a conductor 189 with one terminal of a second relay coil 191, the other terminal of which is connected through a conductor 193 with conductors 173 and 175. Relay coil 191 energizes and controls a pivotally supported latch member 195 which is of substantially hook shape and is adapted to cooperate with and hold contact arm 177 in engagement with contact arm 179 when coil 191 is de-energized.

Let it be assumed that the parts of the apparatus shown in Fig. 4 of the drawings are in the positions shown, i. e., contact arms 163 and 165 are in engagement because of the projection 155 operatively engaging arm 165. If the upper part of the tank is filled with hot water, contact arms 73 and 75 will be in engagement with each other and relay coil 191 is energized whereby latch member 195 will be moved to the position shown in broken lines so that when contact arm 177 is energized and caused to move to its upper position, shown in broken lines, and into engagement with contact member 179 because of the energization of relay coil 171, the latch member 195 will have been moved out of engaging and holding position relatively to contact arm 177 so that as soon as projection 155 has been moved out of operative engagement with contact arm 165, the energizing circuit through relay coil 171 will be opened and the deenergized relay coil 171 will cause lowering of contact arm 177 and thereby cause opening of the energizing circuit through heater 37.

If, on the other hand, the tube 69 is immersed in cold water, contact arm 73 will be out of engagement with contact arm 75 whereby coil 191 will be deenergized and latch arm 195 will be permitted to remain in the position shown in full lines in Fig. 4 so that when arm 177 has been moved upwardly into engagement with contact member 179 it will remain in such position whereby electric heater 37 will be energized at substantially the beginning of the off-peak period.

If, as stated before, the upper part and particularly the upper half of the tank, is filled with hot water, energization of the heater 37 will be delayed a predetermined fixed time the length of which depends upon the peripheral extent of the portion 157 of disc 153 and when contact arm 165 is operatively engaged by portion 159 of the disc, contact arm 165 will again be caused to engage contact arm 163 whereby coil 171 is energized and contact arm 177 is caused to move into and is held in engagement with contact member 179 for the rest of the off-peak period which may be during six hours thereof. However, the details of heater capacity and of the length of time during which it may be energized as well as the adjustment of the lowermost thermostatically controlled switch are all so

selected that the energizing circuit through heater 37 will be opened by disengagement of contact arms 101 and 103 before the end of the off-peak period.

It will be noted that in all of the various forms and modifications which I have illustrated and described, the arrangement is such that the electric heater for the hot water tank is effectively deenergized by thermally controlled means although as has hereinbefore been set forth, the other parts of my system are so constructed and adjusted that the time controlled switching means is not effective to cause final deenergization of the electric heating element since to do so would add an undesirable off-peak load to the circuit in addition to the steadily mounting ordinary load requirements as is shown by the full line load curve 109 at or between the hours of 5 or 6 to 7 a. m. It is, of course, also obvious that the time controlled switching means will be effective to cause final deenergization of the tank water heater in case the thermal control means becomes ineffective for any reason.

It is obvious that my system as shown in the various modifications and as hereinbefore described, includes relatively simple means which are also relatively inexpensive and easily installed and connected for delaying energization of the electric heater of a fluid-containing tank as exemplified by the usual domestic hot water receiving tank, which system is effective to delay energization of the electric heater for a predetermined fixed time, which fixed time of delay is adjustable, in case a predetermined part of the fluid contents of the tank are at relatively high temperature.

The system embodying my invention causes energization of the electric heater at an adjustable fixed time during the off-peak period and the heater is deenergized by a thermostatically controlled switch means, the thermostatic element of which is responsive to the temperature of the water in the lowermost part of the tank.

Certain modifications permit of starting energization of the electric heating element if some of the hot water in the upper part of the tank is withdrawn during the hereinbefore mentioned fixed delay period so that the system embodying my invention is operative in the manner described and to finally cause thermally effected deenergization of the electric heater before the end of the off-peak period and, as has already been hereinbefore set forth, the thermostatic means set forth by me is not subject to what may be called an integration of the temperature of entire contents of the tank but is controlled by the temperature of the water in a predetermined part and preferably in the upper portion of the tank which, as I have found, is that portion containing any hot water which may have been left from the preceding day's use of hot water from the tank.

Various other modifications may be made in the details of the system embodying my invention without departing from the spirit and scope thereof and all such further modifications covered by the appended claims are to be considered as being part of my invention.

I claim as my invention:

1. In an off-peak fluid heating system adapted for a fluid-receiving tank having an electric heater, an electric circuit including switching means for controlling said electric heater, a timing means for preparing said electric circuit so that the electric heater may be energized during

a preselected period of day only and means including a thermostat responsive to the temperature of the fluid in the upper part of the tank for delaying energization of the electric heater a predetermined fixed length of time after said timing means has conditioned said circuit when the temperature of the fluid in the upper part of the tank is above a predetermined value at the instant of preparing said electric circuit by the timing means and remains above said value during said fixed length of time, and means controlled by said timing means for causing energization of said heater at the end of said fixed length of time.

2. In an off-peak water heating system adapted for use with a water tank having an electric heater, an electric circuit for said heater including switching means for controlling said electric heater, a timing means for preparing said circuit so that the electric heater may be energized during a preselected period of day only and means including a thermostat responsive to the temperature of the water in the upper half of the tank effective to delay energization of said heater a predetermined fixed length of time after the timing means has prepared said electric circuit when the temperature of the water in the upper half of the tank is above a predetermined value at the time of said preparation of the circuit and remains above said value during said fixed length of time and effective during said fixed length of time to cause energization of said electric heater on reduction of the temperature of the water in the upper half of the tank below said predetermined value.

3. In an off-peak water heating system for a water-containing tank having an electric heater, a first and a second switch connected in series circuit with each other for controlling said electric heater, clock driven means for causing closure of said first switch during an off-peak period of predetermined duration and means controlled by the temperature of the water in the upper half of the tank for delaying closure of the second switch for a predetermined fixed length of time after closure of said first switch when the temperature of the water in the upper half of the tank is above a predetermined value at the time of closure of said first switch and remains above said value during said fixed length of time.

4. In an off-peak water heating system adapted for use with a water tank having an electric heater, an electric circuit for said heater including switching means for controlling said electric heater, a timing means for preparing said circuit so that the electric heater may be energized during a preselected period of day only and means including a thermostat responsive to the temperature of the water in the upper half of the tank and effective to delay energization of said heater a predetermined fixed length of time after the timing means has prepared said electric circuit, when the temperature of the water in the upper half of the tank is above a predetermined value at the time of said preparation of the circuit and remains at or above said value during said fixed length of time and effective to cause energization of said electric heater on reduction of the temperature of the water in the upper half of the tank below said predetermined value and a thermally-controlled switch responsive to the temperature of the water in the lowermost part of the tank for causing deenergization of said heater when the temperature of substantially all of the water in the lowermost part of the tank has been raised to above said predetermined value.

5. In an off-peak fluid heating system adapted for a fluid-receiving tank having an electric heater, an electric circuit including switching means for controlling said electric heater, a timing means for preparing said electric circuit so that the electric heater may be energized during a preselected period of day only and thermostatic means responsive to the temperature of the fluid in the upper part of the tank for delaying energization of the electric heater a predetermined fixed length of time after said timing means has prepared said circuit when the temperature of the fluid in the upper part of the tank is above a predetermined value at the instant of conditioning of said electric circuit by the timing means and when the temperature of the fluid in the upper part of the tank remains at or above said predetermined value during said time of delay, and clock-controlled means for causing energization of said electric heater at the end of said fixed length of delay time.
6. In an off-peak water heating system for a water containing tank having an electric heater, a first and a second switch connected in series circuit with each other for controlling said electric heater, clock-driven means for causing closure of said first switch at the start of and during an off-peak period of predetermined duration and means including a thermostat subject to the temperature of the water in the upper half of the tank for delaying closure of said second switch for a predetermined fixed length of time after closure of said first switch when the temperature of the water in the upper half of the tank is above a predetermined value at the time of closure of said first switch and for causing closure of said second switch during said fixed length of delay time when the temperature of a predetermined portion of the water in the upper half of the tank drops below said predetermined value.
7. In an off-peak water heating system adapted for a water containing tank having an electric heater, an electric circuit including said heater and switching means for controlling said heater and a timing means indicating the time of day, the improvement comprising means driven synchronously with and by said timing means and thermally actuatable means responsive to the temperature of the water in the upper portion of the tank to cause closing of said switching means at a preset time of day when the tank contains less than a predetermined quantity of hot water in the upper portion thereof and to delay closing of said switching means for a fixed length of time when the tank contains more than a predetermined quantity of hot water in the upper portion thereof.
8. In an off-peak water heating system adapted for a water containing tank having an electric heater, an electric circuit including said heater and switching means for controlling said heater and a timing means indicating the time of day, the improvement comprising means driven synchronously with and by said timing means and thermally-actuable means responsive to the temperature of the water in the upper portion of the tank to cause closing of said switching means at a preset time of day when the tank contains less than a predetermined quantity of hot water in the upper portion thereof and to delay closing of said switching means for a fixed length of time when the tank contains more than a predetermined quantity of hot water in the upper portion thereof and a thermally controlled switching means responsive to the temperature of the water

in the lower portion of the tank for effecting de-energization of said electric heater when the lower portion of the tank contains hot water.

9. In an off-peak water heating system adapted for a water containing tank having an electric heater, an electric circuit including said heater, a first and a second switch in said electric circuit and connected in series circuit with each other for controlling the energization of said electric heater and a continuously operative timing means indicating the time of day, the improvement comprising means driven synchronously with and by said timing means for effecting closing of said first switch at the beginning of a preset off-peak period, and for holding it closed during said period, electromagnetic means for actuating said second switch and means including a thermostat subject to the temperature of the water in the upper portion of the tank for causing said electromagnetic means to close said second switch at the same time that the first switch is closed when the upper portion of the tank contains cold water and to prevent closing of said second switch when the upper portion of the tank contains hot water and means actuated by the means effecting closing of said first switch for causing closing of said second switch by said electromagnetic means a predetermined length of time after closure of said first switch.

10. In an off-peak fluid heating system adapted for a fluid-receiving tank having an electric heater, an electric circuit including switching means for controlling said electric heater, a timing means for preparing said electric circuit so that the electric heater may be energized during a pre-selected period of day only and means including a thermostat responsive to the temperature of the fluid in a predetermined part of the tank for causing energization of the electric heater to be delayed a fixed length of time after the start of said preselected period of day when the temperature of the fluid in said predetermined part of the tank is above a predetermined value at the beginning of said preselected period of day and remains above said value during said delay time.

11. In an off-peak fluid heating system adapted for a fluid-receiving tank having an electric heater, an electric circuit including switching means for controlling said electric heater, a timing means for preparing said electric circuit so that the electric heater may be energized during a preselected period of day only and means including a thermostat responsive to the temperature of the fluid in a predetermined part of the tank for causing energization of the electric heater to be delayed a fixed length of time after the start of said preselected period of day when the temperature of the fluid in said predetermined part of the tank is above a predetermined value at the beginning of said preselected period of day and remains above said value during said delay time and a thermally-controlled switch means responsive to the temperature of the fluid in the lowermost part of the tank for causing deenergization of said electric heater when the temperature of the fluid in the lowermost part of the tank has been raised to a predetermined value.

12. In an off-peak water heating system for a water containing tank having an electric heater, a first and a second switch connected in series circuit with each other for controlling said electric heater, clock driven means for causing closure of said first switch during an off-peak period of predetermined duration and means controlled by the temperature of the water in the upper half

of the tank for delaying closure of the second switch for a predetermined fixed length of time after closure of said first switch when the temperature of the water in the upper half of the tank is above a predetermined value at the time of closure of said first switch and remains above said value during said fixed length of time and a thermally-controlled switch means responsive to the temperature of the fluid in the lowermost part of the tank for causing deenergization of said electric heater when the temperature of the fluid in the lowermost part of the tank has been raised to a predetermined value.

13. In an off-peak water heating system for a water containing tank having an electric heater, a first and a second switch connected in series circuit with each other for controlling said electric heater, clock driven means for causing closure of said first switch during an off-peak period of predetermined duration and means including a thermostat controlled by the temperature of the water in a predetermined part of the tank for delaying closure of the second switch for a predetermined fixed length of time after closure of said first switch when the temperature of the water in the predetermined part of the tank is above a predetermined value at the time of closure of said first switch and remains above said value during said fixed length of time and for causing closure of said second switch at the end of said delay time.

14. In an off-peak fluid heating system adapted for a fluid-containing tank having an electric heater, means including an electromagnetic switch controlling the energization of the heater and two switches connected in series electric circuit with each other and controlled respectively in accordance with time and with the temperature of the fluid in the upper part of the tank and jointly controlling the energization of said electromagnetic switch to delay energization of the heater for an adjustably preset fixed time after the start of an off-peak period in case the fluid in the upper part of the tank is hot at the start of an off-peak period and remains hot during said preset fixed time of delay, and to cause energization of said heater at the end of said fixed delay time irrespective of the temperature condition of the fluid in the upper part of the tank.

15. In an off-peak fluid heating system adapted for a fluid-containing tank having an electric heater, means including an electromagnetic switch controlling the energization of the heater and two switches connected in series electric circuit with each other and controlled respectively in accordance with time and with the temperature of the fluid in the upper part of the tank and jointly controlling the energization of said electromagnetic switch to delay energization of the heater for an adjustably preset fixed time after the start of an off-peak period in case the fluid in the upper part of the tank is hot at the start of an off-peak period and remains hot during said preset fixed time of delay, and to cause energization of said heater at the end of said fixed delay time irrespective of the temperature condition of the fluid in the upper part of the tank and thermally-actuable heater control switch means responsive to the temperature of the fluid in the lower part of the tank for causing deenergization of the electric heater in case substantially all of the fluid in the tank is hot before the end of an off-peak period.

16. In an off-peak fluid heating system adapted for a fluid-containing tank having an electric

heater, means including an electromagnetic switch controlling the energization of the heater and two switches connected in series electric circuit with each other and controlled respectively in accordance with time and with the temperature of the fluid in the upper part of the tank and jointly controlling the energization of said electromagnetic switch to delay energization of the heater for an adjustably preset fixed time after the start of an off-peak period in case the fluid in the upper part of the tank is hot at the start of an off-peak period and to cause energization of said electric heater during said delay time in case withdrawal of hot fluid from the tank during said delay time subjects the switch controlled by the temperature of the fluid in the upper part of the tank to cold fluid.

17. In an off-peak fluid heating system adapted for a fluid-containing tank having a single electric heater, means including an electromagnetic switch controlling the energization of the heater and two switches connected in series electric circuit with each other and controlled respectively in accordance with time and with the temperature of the fluid in the upper part of the tank and jointly controlling the energization of said electromagnetic switch to delay energization of the heater for an adjustably preset fixed time after the start of an off-peak period in case the fluid in the upper part of the tank is hot at the start of an off-peak period and remains hot during said preset fixed time of delay, and to cause energization of said heater at the end of said fixed delay time irrespective of the temperature condition of the fluid in the upper part of the tank and for causing reenergization of the heater in case of withdrawal of sufficient hot fluid from the tank during the off-peak period to subject said thermally-actuable heater control switch to cold fluid.

18. In an off-peak fluid heating system adapted for a fluid-containing tank having a single electric heater, means including an electromagnetic switch controlling the energization of the heater, a continuously operative timing means, a switch controlled by said timing means, a thermally-actuable switch responsive to the temperature of the fluid in the upper part of the tank, electric connections between said switch controlled by said timing means, said thermally-actuable switch and said electromagnetic switch to cause said switch controlled by said timing means and said thermally-actuable switch to jointly control the energization of said electromagnetic switch to delay energization of said heater for a preset fixed time after the start of an off-peak period in case the fluid in the upper part of the tank is hot at the start of an off-peak period and remains hot during said preset fixed time of delay and a second switch controlled by said timing means and

5 electrically connected in shunt to said thermally-actuable switch to cause energization of said electromagnetic switch and energization of said heater at the end of said preset fixed delay time irrespective of the fluid temperature in the upper part of the tank.

19. In an off-peak fluid heating system adapted for a fluid-containing tank having a single electric heater, means including an electromagnetic switch controlling the energization of the heater, a continuously operative timing means, a switch controlled by said timing means, a thermally-actuable switch responsive to the temperature of the fluid in the upper part of the tank, electric 10 connections between said switch controlled by said timing means, said thermally-actuable switch and said electromagnetic switch to cause said switch controlled by said timing means and said thermally-actuable switch to jointly control the energization of said electromagnetic switch to delay energization of said heater for a preset fixed time after the start of an off-peak period in case the fluid in the upper part of the tank is hot at the start of an off-peak period and remains hot during said preset fixed time of delay and a second switch controlled by said timing means and electrically connected in shunt to said thermally-actuable switch to cause energization of said electromagnetic switch and energization of said heater at the end of said preset fixed delay time irrespective of the fluid temperature in the upper part of the tank and thermally-actuable heater control switch means responsive to the temperature of the fluid in the lower part of the tank for causing deenergization of the electric heater in case substantially all of the fluid in the tank is hot before the end of an off-peak period and for causing reenergization of the heater in case of withdrawal of sufficient hot fluid 25 from the tank during the off-peak period to subject said thermally-actuable heater control switch to cold fluid.

20. In an off-peak water heating system adapted for a water containing tank having an electric heater, an electric circuit including said heater and switching means for controlling said heater and a timing means indicating the time of day, the improvement comprising means driven synchronously with and by said timing means and thermally actuable means responsive to the temperature of the water in the upper portion of the tank jointly effective to cause a preset fixed delay in closing of said switching means after the start of an off-peak period in case the tank contains more than a predetermined quantity of hot water in the upper portion thereof and to cause energization of said electric heater as soon as withdrawal of hot water from the tank during the preset delay period subjects said thermally actuable means to cold water.

CLARK M. OSTERHELD.
